UNITED STATES PATENT OFFICE.

JOHN L. CLINE AND WILLIAM HENDERSON, OF LANSING, KANSAS.

PEN-WIPER.

1,260,644.

Specification of Letters Patent. Patented Mar. 26, 1918.

Application filed June 10, 1916. Serial No. 103,008.

To all whom it may concern:

Be it known that we, JOHN L. CLINE and WILLIAM HENDERSON, citizens of the United States, residing at Lansing, in the county 5 of Leavenworth and State of Kansas, have invented new and useful Improvements in Pen-Wipers, of which the following is a specification.

Our invention relates broadly to the class 10 of pen-wiping appliances and has special relation to a combined pen-wiper and rack.

An object of our invention is to provide a device of the foregoing nature which is characterized by elements of strength and 15 lightness to a marked degree, yet one which is efficient in operation and cheap to manufacture.

Pen-wipers of the ordinary desk type have proven inefficient in many ways; first, 20 the absorbing means does not wipe the pen clean because it does not travel entirely over the wet surface of the same. For instance, if a pen were inserted into a sponge, portions of the sponge will normally contact the 25 pen point so as to absorb a quantity of the ink contained thereon; however, these wet portions still remain in engagement with the point, and consequently the latter is not entirely dry when withdrawn from the device.

30 In our invention we have provided a stationary roller, having an absorbent face, the said face being in a concave form so as to receive the convex periphery of a second roller, also having an absorbent face.

35 While the first roller is stationary upon the frame-work of the device, the second roller is pivoted and when the pen is wiped the handle of the latter rests upon a portion of the supporting means of the pivoted roller

40 so that the weight of the operator's hand forces the pivoted roller in engagement with the stationary roller and securely grasps the pen. As the pen is withdrawn from this position the rollers are turned upon their 45 respective pivoted points so that different absorbent faces contact with the pen in the manner obvious so that all the ink will be removed therefrom, at the same time obviating the extreme point of the pen from contacting with any fibrous material whatsoever.

It is also pointed out that by the provi-

sion of a concave and convex roller the upper face of the pen will be efficiently cleaned by the concave roller while the convex roller 55 engages the under face of the pen point so as to remove all of the ink thereon.

With the above and other objects in view our invention relates to such details of construction and in the engagement and combination of parts as will be hereinafter fully described and specifically set forth in the appendant claims.

In describing our invention in detail reference will be had to the accompanying 65 drawings wherein like numerals represent like or corresponding parts throughout the several views and in which:

Figure 1 is a side elevation of our invention in its preferred form.

Fig. 2 is a plan view of the device.

Fig. 3 is a longitudinal sectional view showing parts in elevation and the specific manner in which the pen point is engaged by the concave and convex rollers.

In the accompanying drawings wherein is illustrated the preferred form of our invention, the numeral 10 designates a base plate constructed preferably of metal or material of the like consistency from which 80 project upwardly and near the ends thereof, pairs of supporting arms 11 and 12.

Upon reference to the drawings it will be seen that the arms 12 are considerably shorter than the others, this being for the 85 purpose hereinafter fully set forth. Enlarged portions 13 and 14 respectively are provided upon each of the arms, the enlargements 13 being connected together by a shaft 15 carrying a head portion 16, while 90 the enlargements 14 have journaled therethrough a pin 17.

A roller is provided upon the shaft 15, and spaced from the enlargements through the medium of the concavo-convex disks 18, concave portion of the disks being in engagement with the enlargement so that only a medium amount of friction is generated when the roller is revolved.

As will be recognized the roller is constructed of an absorbent material such for instance, as a blotting medium and as a concave face 19.

A member 20 is pivoted upon the pin 17

and has projecting upwardly therefrom, at its rear extremity a finger 21, the latter supporting sections 22 of a resilient material, as is shown. The upper faces of the sections 22 are formed concave to conform with the contour of the handle of the pen as it rests thereon as is clearly shown in Fig. 3.

10 Arms 23 project from the forward extremity of the member 20 and have journaled therethrough a stub shaft 24, the latter supporting the roller 25. This roller is also formed of an absorbent material and spaced from the arms through the medium of concavo-convex disks 26.

15 Consistent with the foregoing description the roller 25 has a convex face which when in the position shown in Fig. 3 enters the concave face of the roller 19 in the manner shown.

20 A section of blotting material 27 is disposed between the supports 11 and 12 upon which normally rests the roller 25. By the provision of this blotting material it will be
25 recognized that if any ink should drop from the pen it would be absorbed thereby before reaching the desk or other support of the device.

Racks of the usual form such as designated by the numeral 28 are provided adjacent to the supporting arms 11 and 12 and receive the pen substantially as shown in Fig. 1.

From the foregoing it is thought that the advantages and novel features of our invention will be readily understood.

35 We desire it to be understood that we may make slight changes in the construction and in the arrangement and combination of parts without departing from the spirit of our invention, provided, however, such changes 40 fall within the scope of the subjoined claims.

Having thus fully described our inven-

tion, what we claim as new and desire to secure by Letters Patent is:

1. A pen-wiper comprising a standard, a relatively stationary wiping roller journaled on the standard, a wiping roller coacting with the relatively stationary roller, and supporting means for the coacting wiping roller, said means being operative to move the coacting roller toward the relatively stationary roller when a pen-point is inserted between the rollers. 1 1

2. A pen-wiper comprising a standard, relatively movable absorbent rollers carried by the standard and means actuated by a pen-holder for urging one of the rollers against the other upon the insertion of a pen-point between the rollers. 55

3. A pen-wiper comprising a standard, an absorbing roller journaled on the standard, a frame pivoted on the standard, a coacting absorbing roller journaled in the frame, and a rest arranged on the frame for depressing the frame and moving the frame carried roller toward the standard carried roller when pressure is applied to said rest. 60 65

4. A pen-wiper comprising a standard, a relatively fixed absorbing roller having a concave periphery journaled on the standard, a roller frame journaled on the standard, the frame having a grooved extension, and a coacting absorbent roller journaled in the frame, said roller having a convex periphery to enter the relatively fixed absorbing roller concavity when moved toward said roller when the frame is depressed at the grooved extension. 75

JOHN L. CLINE.

WILLIAM HENDERSON.
